STOVE

John D. Robinson, Modesto, Calif.

Application March 8, 1937, Serial No. 129,542

1 Claim. (Cl. 126—9)

This invention relates generally to a portable stove and in particular relates to a collapsible stove adapted for use by campers, persons in pack trains, and on any occasion where a compact stove unit is requisite due to limited carrying space.

The principal object of my invention is to provide a collapsible stove which when collapsed or dismantled occupies a minimum of space and is light in weight; the stove in assembled position affording a good sized upper cooking surface as well as a small oven.

A further object of my invention is to provide a stove, of the character described, which is so constructed that the fire is kindled directly on the ground and thus when the stove is to be dismantled, it is not necessary to clean out any material amount of ashes.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

30 Figure 1 is a perspective view of the stove as collapsed for transportation.

Figure 2 is a perspective view of the stove as assembled for use.

Figure 3 is a sectional elevation on line 3—3 of Fig. 2.

Figure 4 is a cross section taken on line 4—4 of Fig. 2.

Referring now more particularly to the characters of reference on the drawings, my improved collapsible stove is constructed from relatively light sheet metal and comprises the following parts:

Two rectangular box-like sections 1 and 2 open at adjacent ends are arranged for telescoping movement from the position shown in Fig. 1 to the position shown in Fig. 2 and vice versa; the section 2 sliding within the section 1. If desired, the top of section 2 may be inwardly creased or ribbed as at 3, to strengthen the same against sagging when cooking utensils or the like are placed thereon. The outer end of section 2 is provided with a relatively large hinged fire door 4 having a suitable latch 5; a sliding draft control door 6, of relatively small size, being disposed beneath the door 4. One

side of section 1 is provided with a rectangular opening, said opening being normally closed by means of a door 7 hinged adjacent the opening and having a latch 8 to maintain the door in such position. When the stove is in assembled position, an oven 9 is removably disposed in section 1 transversely thereof and is open to said one side of the section through the opening therein. Flanges 10 maintain the outer end of the oven in place while a depending skirt 11 supports the inner end thereof from the bottom of section 1.

The oven is shallower in height than section 1, as shown in Fig. 3, while extending substantially the full width thereof, as shown in Fig. 4. In this manner, the fire can pass all about the top, bottom and sides of the oven.

A flue 12 having a damper 13 disposed therein is mounted on the outer end of section 1 and in communication with the interior thereof near the bottom. A removable chimney comprising a plurality of relatively short interfitting and interchangeable sections 14 is mounted vertically on the flue.

The bottom of section 2 is entirely open, as shown in Fig. 3, except for a narrow flange portion 15 adjacent the outer end which strengthens the section and prevents warping. As section 2 is substantially bottomless, a fire may be kindled directly on the ground and then, when the fire is out, the stove may be picked up and collapsed without first having to clean out the ashes. Any small amount of ashes on flange 15 or on the bottom of section 1 can be readily shaken out of the stove before it is dismantled.

After use, the assembled stove is collapsed and packed for transportation in the following manner. The door 7 is opened and the removable oven 9 removed from section 1 through the opening in the side thereof; the door being then locked closed. The chimney sections 14 are separated and the lowermost one removed from the flue. Sections 1 and 2 are separated and the oven 9 and chimney sections 14 are placed within section 1; their dimensions being such as to permit this to be readily done without clamping. Then, section 2 is telescoped into section 1 and the stove is ready for transportation as illustrated in Fig. 1.

From the foregoing description it will be readily seen that I have produced such a device as substantially fulfills the objects of the invention as set forth herein.

While this specification sets forth in detail the present and preferred construction of the de-

vice, still in practice such deviations from such detail may be resorted to as do not form a departure from the spirit of the invention, as defined by the appended claim.

5 Having thus described my invention, what I claim as new and useful and desire to secure by Letters Patent is:

A portable stove including a pair of non-collapsible metallic sections rectangular in cross section and telescopically arranged, one of said sections having an opening in one side thereof, a door mounted on said section and arranged to close the opening and an oven of substantially

the same cross sectional size and configuration as said opening and of a depth only slightly less than the width of said one section, the oven being adapted for removable placement through said opening and positioning transversely within said one section when the telescopic sections are extended; the oven being shorter than said sections when telescoped and of a width whereby it may be removed through the opening from such transverse position and disposed longitudinally within the sections when so telescoped. 10

JOHN D. ROBINSON.
